Application July 14, 1934, Serial No. 735,102

12 Claims. (Cl. 290—36)

This invention relates to a system of control for the starting apparatus of internal combustion engines and particularly to those engines used on automotive vehicles.

5 The present invention relates to improvements in the type of apparatus shown in the copending application of John B. Dyer, Serial No. 653,983, filed January 28, 1933 for Engine control system. That application discloses a circuit which requires the closing of the ignition switch and the closing of a switch coordinated with the engine throttle actuator in order to establish a relay magnet circuit whereby a starter control relay switch is closed in order to effect the closing of 15 other circuits which will cause an electric starter to operate to crank the engine. The circuit of the battery and the relay magnet and the two switches referred to include a part of the generator circuit.

20 It is one of the objects of the present invention to provide a circuit for the relay magnet which is independent of the generator so that the starter control system would not be rendered inoperative simply on account of failure of the generator to complete a circuit to the battery at the time the generator is at rest. Such failure might occur due to poor electrical contact between the generator brushes and the commutator. In order to accomplish this object the circuit of the relay comprises a storage battery which is grounded, a switch coordinated with the ignition switch, a switch coordinated with the engine throttle actuator, the relay magnet winding and a switch which connects the circuit to the battery through ground while the generator is not running, said last mentioned switch being inoperative when the generator is connected to the battery by the reverse current or cut-out relay. This third switch of the circuit of the engine starter control relay magnet includes a movable contact actuated by the armature of the reverse current relay.

25 Further objects and advantages of the present invention will be apparent from the following description, reference being had to the accompanying drawing wherein a preferred embodiment of the present invention is clearly shown.

In the drawing:

30 Fig. 1 of the drawing is a wiring diagram illustrating the present invention.

Fig. 2 is a detail section of a suction operated switch.

35 In the drawing, 20 designates a generator grounded at 21 and connected by a wire 22 with

the current winding 23 of a reverse current relay 24. Winding 23 is connected with the frame 25 of relay 24, which frame supports a leaf spring hinge 26 to which one end of the armature 27 is attached. Armature 27 carries a contact 28 engageable with its stationary contact 29 carried by bracket 30 connected by wire 31 with an ammeter 32 connected by wires 33 and 34 with the battery 35 grounded at 36. This completes the generator-to-battery circuit. A voltage coil 37 is connected with the relay frame 25 and is grounded at 38. The frame 25 supports a core 39 which is surrounded by the windings 23 and 37 although these windings are shown in the drawing as separated from the core 39. The relay contacts 28 and 29 are closed to complete the battery charging circuit by the magnetic action produced by current flowing through the voltage winding 37 after the generator has attained a certain voltage. When the contacts 28 and 29 are closed, current then flows through the winding 23 which then cooperates with winding 37 to hold the armature 27 in position to maintain the contact 28 in engagement with the contact 29. It is therefore apparent that the relay can be adjusted so that its contacts will not be separated due to the action of the spring hinge 26 until after the voltage of the generator has fallen substantially below that voltage required for the closing of the relay contacts 28 and 29.

30 The main engine cranking circuit comprises the battery 35, wire 34, switch contact 40, movable contact 41, switch contact 42, wire 43, starting motor 44 which is grounded at 45, and battery ground connection 36. The starting motor 44 operates the shaft 46 along which slides a sleeve 47 which is splined on the shaft 46 and which is operatively connected through a one way or overrunning clutch 48 with a pinion 49 engageable with the engine fly wheel gear 50. The sleeve 47 is surrounded by a grooved collar 51 which is slidable along the sleeve 47 but normally is held against a shoulder 52 at the left end of the sleeve 47 by a spring 53 interposed between the collar 51 and the clutch 48. The collar 51 is caused to move toward the right in the drawing by lever 54 pivotally mounted upon a shaft 55 and carrying at its lower end a pin 56 received by the groove of the collar 51. Movement of the lever 54 counterclockwise will cause the sleeve 47 to be moved toward the right and the pinion 49 to become engaged with the fly wheel gear 50. The pinion 49 is withdrawn from the gear 50 by the operation of a spring 57 which

surrounds the shaft 55 and bears at one end against a stationary stop 58 and at the other against a stop 59 carried by the lever 54.

The lever 54 is actuated and the switch 40, 41, 5 42 is closed by electromagnetic means which comprises a solenoid core 60 and a solenoid armature 61 which are surrounded by electromagnet windings 62 and 63. The solenoid core 60 is provided with a central bore for receiving a 10 horizontally slideable plunger or rod 64 provided with two shoulders 166 and 179 between which an insulatingly mounted movable contact 41 is relatively slideable. A spring 174 urges the contact 41 against the shoulder 166. The rod 64 15 is normally held in the position shown in the drawing with its shoulder 179 bearing against the magnet core 60 due to the action of a spring 164 bearing at one end against the shoulder 166 and at the other end against a stationary part 20 156 having a projection 162 telescopically fitting within a recess or central bore 161 in the rod 64. The solenoid armature 60 is connected by a pin 74 with a link 75 which carries a stud 76 received by a slot 77 provided in the upper end 25 of the lever 54.

When sufficient current passes through the windings 62 and 63, the armature 61 is caused to move toward the left in order to effect counter-clockwise movement of the lever 54 and the 30 movement of the pinion 49 into mesh with the engine gear 50. This movement of the solenoid 61 also causes the rod 64 to move to the left carrying with it, due to the action of the spring 174, the switch contact 41 which is yieldingly pressed into engagement with the contacts 40 and 42 due to the yielding action of the 35 spring 174. When this occurs, current will flow from the battery to the motor 44 thereby causing rotation of its armature shaft 46 and the 40 pinion 49 driven thereby through the splined sleeve 47 and the overrunning clutch 48, thereby causing the flywheel gear 50 to rotate and the engine to be cranked for starting purposes. Should the engine fail to start and the pinion 49 fail to 45 be withdrawn from the fly wheel gear 50 by the action of the spring 57, it is possible to open the circuit of the starting motor by disconnecting the magnet coil windings 62 and 63 from the storage battery, the connections to which are 50 to be described later. When the magnet coils 62 and 63 are deenergized, movement of the contact 41 away from the contacts 40 and 42 by the action of spring 164 may take place due to the fact that the solenoid 61 may move toward 55 the right slightly although the lever 54 may not be turned. This is possible due to the lost motion connection provided by the pin 76 and the slot 77 between the solenoid armature 61 and the lever 54.

60 Should the end faces of the teeth of the pinion 49 abut with the end faces of the gear 50 before meshing, it is possible to close the motor circuit in order that the pinion 49 may be rotated into meshing relation with the engine gear 50. 65 This is possible due to the fact that the motor switch 40, 41, 42 can be closed before the meshing of pinion 49 with gear 50 takes place. The solenoid armature 61 moves to close the motor switch and to move the pinion 49 toward the gear 50; but, after the pinion 49 collides with the gear 50, the spring 53 is compressed beyond its initial state of compression. Then when the motor shaft 46 turns to relieve the condition of gear 70 tooth abutment, the spring 53 is released quickly 75

to snap or jump the pinion 49 into engagement with the engine gear 50.

The circuit for connecting the magnet windings 62 and 63 with the storage battery 35 comprises the following circuit: Battery 35, wire 34, contact 40, frame 81 of the starter control relay 80, leaf spring hinge 82, armature 83, contact 84, stationary contact 85, bracket 86, wire 87, winding 63, ground connection 88 and battery ground connection 36. Stop 83a limits upward movement of 10 armature 83. The circuit of the other winding 62 includes the foregoing circuit as far as the bracket 86. From the bracket 86 a wire 90 leads out to connect with the coil 62 which is connected by wire 90a with the contact 42. The 15 circuit of coil 62 is completed to the battery through the motor 44 and ground connections 45 and 36. It is apparent that when the contacts 84 and 85 of the starter relay 80 are closed, current will flow through both windings 62 and 20 63 to cause the solenoid 61 to move toward the left in order to shift the pinion 49 into engagement with the gear 50 and to close the motor switch 40, 41, 42. When the motor switch closes, the winding 62 will be short circuited. The 25 winding 62 is made preferably of relatively coarse wire whereas the winding 63 is constructed of relatively fine wire. Both windings 62 and 63 are required to draw the armature 61 across to the core 60 but, when this relation has been 30 established, the one winding 63 is all that is required to maintain this relationship. Therefore, the winding 62, which consumes the greater amount of current is short circuited so that the starting motor will have adequate current 35 for cranking the engine.

The circuit of the engine starter control relay 80 comprises battery 35, wire 34, wire 33, ammeter 32, wire 91, stationary contact 92 of ignition switch 93, movable contact 94, stationary contact 95, wire 96, switch 97, wire 98, relay magnet coil 99 surrounding core 100, wire 101, bracket 102, contact 103 cooperating with movable contact 104 insulatingly carried by armature 27 of cut-out relay 24, wire 105, and ground returns 38, 36 to battery 35. When the movable switch contact 94 of ignition switch 93 engages contacts 92 and 95 it also engages a contact 106 connected by a wire 107 with the ignition apparatus of the engine. The switch 97 is one which is closed manually and is open automatically when the engine starts. The switch 97 is preferably actuated by the engine throttle actuator or accelerator pedal. It is opened automatically preferably by means responsive to engine intake 50 suction. The switch contacts 103, 104 of the cut-out relay 24 are normally closed.

To start the engine, the operator turns on the ignition switch 93 to cause the contact 94 to engage contacts 92, 95 and 106. The operator 60 closes the switch 97 preferably by means co-ordinated with the accelerator. This causes current to flow from the battery through the coil 99 of the starter control relay 80 whereupon contacts 84 and 85 are closed, whereupon the 65 magnet coils 62 and 63 are energized to effect the shifting of the starter pinion 49 into mesh with the engine fly wheel gear and then closing of the main motor switch 40, 41, 42. The engine therefore starts in the manner described. When 70 the engine becomes self-operative, suction produced by the engine will open the switch 97; and, in response to the voltage of the generator 20 driven by the engine, the switch 103, 104 will be open. Hence the circuit of the coil 99 of 75

the starter control relay 80 is opened by two switches connected in series to insure the discontinuance of the engine starting function as soon as possible after the engine becomes self-operative and the prevention of the operation of the starter thereafter or until the engine has stopped.

The construction of the magnet may be varied within certain limits, but it is desirable that the 10 coil 63 shall contain a smaller number of turns than the coil 62, and the resistance of the coil 63 should be higher than the coil 62 so that the flow of current through the coil 63 is as low as possible to insure that the armature of the 15 magnet be held in switch closing position during the cranking operation, so as to change that position as little as possible. It has been found desirable to provide coils having such resistances that for a six volt battery system, the flow of 20 current through coil 63 is substantially from 8 to 10 amperes and through the coil 62 from 40 to 50 amperes before the starter switch is closed. The flow of current through the coil 62 is very 25 brief, as it takes an almost imperceptible time to effect closing of the starting motor switch so that during most of the starting operation there is only from 8 to 10 amperes flowing through the coil 63 to hold the starting motor switch closed and the pinion in gear-engaging 30 position.

It has been found that in order to cause proper opening of the main starter switch 40, 41, 42 upon opening of the ignition switch or the switch 35 97, the number of turns in the inner, or "pull in" coil 62 of the starter magnet must be somewhat greater than the number of turns in the outer, or "hold in" coil 63. This is true because when either switch above referred to, is opened while the starter switch is closed, current will flow 40 from the battery through the starter and thence through the coils of the starter magnet to ground, the direction of current in the inner coil being the reverse of that in the outer coil.

As a concrete example of the operation it 45 may be assumed that the switch 97 is opened by suction and the starter switch should open immediately. On opening of switch 97, however, current will flow from the battery to ground through connection 36 and from the battery 50 through wire 34, the starter switch 40, 41, 42, wire 90a through the coil 62, thence through wire 90, wire 81, the coil 63 to ground 88, the direction of flow through coil 62 being reversed 55 while the direction of flow through coil 63 remains the same. At this time the coils tend to neutralize each other and in order to insure that the magnetic flux passes through the zero point immediately, a slightly larger number of turns are used in the inner coil 62. The outer 60 coil 63 may comprise 122 turns of #16 B. E. copper wire, and the inner coil 62 127 turns of #11½ B. E. copper wire. With this arrangement, as the flux passes through the zero point upon reversal of 65 polarity of the inner coil 62 on opening of the suction operated switch 97, the magnet becomes completely deenergized and the starter switch is opened by the spring 164, as the spring 57 retracts the armature 61 and demeshes the pinion 48.

Theoretically, it might be possible to effect 70 opening of the starter switch 40, 41, 42, with coils having the same number of turns, but owing to the residual magnetism of the magnet, inequalities in the wire resulting in varying resist-

ances, and manufacturing inaccuracies, it is impossible to use coils of the same number of turns as the magnetic flux might not reach zero value. To make sure that the flux pressure does always pass through the zero point, it is necessary to 5 provide at least a few more turns in the inner coil than the outer.

An improved form of accelerator-closed, engine-suction-opened switch 97 is disclosed in the copending application of John B. Dyer, Serial 10 No. 643,375, filed November 19, 1932.

The suction operated switch 97 is shown in detail in Fig. 2 and comprises a diaphragm housing composed of two sheet metal shells 100 and 101, which are secured together at their periphery to form a fluid-tight joint and between which a diaphragm 102 is clamped. Secured to the shell 101 of the diaphragm chamber is a cup-shaped shell 103 which is closed by a disc of insulating material 104 in which are secured additional contacts 105. Extending through the insulating material 104 and journaled therein for rotation is a stud 106 to which is secured by riveting or in any other convenient way, a lever arm 107 adapted to be connected to the accelerator pedal for operation therewith. The stud 106 carries a sleeve 108 which is provided with slots 109 diametrically opposed from each other and received in these slots is a movable contact 110 which is rotated with the sleeve when the 25 arm 107 is operated by the accelerator pedal. This contact is carried by a sleeve 111 which fits within the aforementioned sleeve 108 and is carried by the diaphragm 102, previously referred to. The diaphragm is normally held in the position shown in the drawing by a spring 111 which pushes the diaphragm downwardly and tends to force the movable contacts toward the insulating member. A torsion spring 112, one end of which is connected to one of the two pins 113, which 30 are secured in the housing 103, and the other end of which is connected to the movable contact, normally holds the contact in such position that when it is forced downwardly by the spring 111, as previously described, it will not engage 35 with the two fixed contacts 105.

The sleeve 108 is provided with shoulders on which the movable contact is adapted to rest during the operation of the engine.

The closing of the switch is effected by movement of the arm 107 which rotates the movable contacts into engagement with the two fixed contacts. When this takes place and the other control switches in the circuit are closed, the engine starts to run and when the suction becomes effective when the engine begins to run under its own power, the diaphragm is pulled upwardly lifting the movable contact out of engagement with the two fixed contacts and the torsion spring previously referred to then rotates the 55 movable contact in the reverse direction so that it will rest upon the previously described shoulders if the suction falls due to any increase in load or from any other cause in order to prevent any possible closing of the switch during 60 operation of the engine when such decrease in suction takes place. This switch is the one which is illustrated in the previous application Serial No. 643,375 and which is shown in greater detail 65 therein.

An improved form of magnetic starter switch and starter switch relay unit is disclosed in the copending application of John B. Dyer, Serial No. 653,983, filed January 28, 1933.

The claims of this application are directed to 75

the system of control, particularly to the starter switch relay circuit independent of the generator. The advantage of this circuit over one which includes the generator is readily apparent since it is known that a generator having a gummy commutator might make very poor electrical contact with its brushes while at rest, although, after its commutator had rotated a few revolutions, the generator might be thereafter operative to charge the battery. Any such possibility is avoided by the present invention, since the ground return to the battery of the starter switch relay magnet circuit is provided not by way of the generator and its ground return, but by way of a separate normally grounded switch the contacts of which are separated by the action of the cut-out relay to connect the generator with the battery for charging purposes. Thus the starter control circuit is prevented from function not only by the engine-suction responsive switch 97 but by a switch responsive to generator operation. By making additional use of the cutout relay, this additional preventative switch is provided at but small additional expense. Furthermore, the cut-out relay is well adapted for such additional use since it has the characteristic of holding its armature in attracted position until the generator speed has dropped to a very low value.

While the embodiment of the present invention as herein disclosed, constitutes a preferred form, it is to be understood that other forms might be adopted, all coming within the scope of the claims which follow.

What is claimed is as follows:

1. In an engine starter control system, the combination which comprises, a storage battery, an engine driven generator for charging the battery, a cut out relay associated therewith, an electric starting motor for starting the engine, and a control circuit operated by said battery for connecting said battery with said electric starting motor, said control circuit including a relay magnet winding, a switch operated by the cut out relay for connecting said relay magnet with the battery independently of both the generator and the starting motor, and including a second switch operated in response to engine operation.

2. In an engine starter control system, the combination which comprises, a storage battery, an engine driven generator for charging the battery, a cut out relay associated therewith, an electric starting motor for starting the engine, and a control circuit operated by said battery for connecting said battery with said electric starting motor, said control circuit including a relay magnet winding, a switch operated by the cut out relay for connecting said relay magnet with the battery independently of both the generator and the starting motor, including a manually closed switch and a normally closed switch opened in response to suction produced by the engine.

3. In an engine starter control system, the combination which comprises, a storage battery, an engine driven generator for charging the battery, a cut out relay associated therewith, an electric starting motor for starting the engine, and a control circuit operated by said battery for connecting said battery with said electric starting motor, said control circuit including a relay magnet winding, a switch operated by the cut out relay for connecting said relay magnet with the battery independently of both the generator and the starting motor, said means including a manually closed switch and the switch operated by the cut

out relay, said last named switch being normally closed and opened in response to the voltage of the generator, and a switch operated by engine suction.

4. In an engine starter control system, the combination which comprises, a storage battery, an engine driven generator for charging the battery, a cut out relay associated therewith, an electric starting motor for starting the engine, and a control circuit operated by said battery for connecting said battery with said electric starting motor, said control circuit including a relay magnet winding and means for connecting said relay magnet with the battery independently of both the generator and the starting motor, and including, in series, a manually closed switch, a normally closed switch opened in response to suction produced by the engine, and a normally closed switch operated by the cut out relay and adapted to be opened in response to generator operation.

5. In an engine starter control system, the combination which comprises, a storage battery, an engine driven generator for charging the battery, a cut-out relay for connecting the generator with the battery, an electric starting motor for starting the engine, and a control circuit operated by said battery for connecting said battery with said electric starting motor, said control circuit including a relay magnet winding and means for connecting said relay magnet with the battery independently of both the generator and the starting motor and including a normally closed switch opened in response to the operation of the cut-out relay to connect the generator with the battery, and a second normally closed switch adapted to be opened by engine suction.

6. In an engine starter control system, the combination which comprises, a storage battery, an engine driven generator for charging the battery, a cut-out relay for connecting the generator with the battery and including a magnet and armature operated thereby, an electric starting motor for starting the engine, and a control circuit operated by said battery for connecting said battery with said electric starting motor, said control circuit including a relay magnet winding and means for connecting said relay magnet with the battery independently of both the generator and the starting motor, and including a normally closed switch having a movable contact insulatingly supported by the armature of the cut-out relay and opened in response to the operation of the cut-out relay to connect the generator with the battery, and a second control switch adapted to be opened by engine suction.

7. In an engine starter control system, the combination comprising, a storage battery, an engine driven generator for charging the battery, a cut out relay for connecting the generator with the battery, a starting motor adapted to receive current from said storage battery, a starter switch for controlling the operation of said starting motor, an electromagnet having a winding for operating said starter switch, a magnetic switch in circuit with the winding of said magnet and controlling the operation of said magnet, a control circuit for the magnetic switch for connecting the magnetic switch with the battery independently of both the generator and the starting motor including two engine operated switches, one of which is operated by said cut out relay.

8. In an engine starter control system, the combination comprising, a storage battery, an

- engine driven generator for charging the battery, a cut out relay for connecting the generator with the battery, a starting motor adapted to receive current from said storage battery, a starter switch for controlling the operation of said starting motor, an electromagnet having a winding for operating said starter switch, a magnetic switch in circuit with the winding of said magnet and controlling the operation of said magnet, a control circuit for the magnetic switch for connecting the magnetic switch with the battery independently of both the generator and the starting motor including a switch operated by engine suction and a second switch operated by 15 said cut out relay.
9. In an engine starter control system, the combination comprising, a storage battery, an engine driven generator for charging the battery, a cut out relay for connecting the generator with the battery, a starting motor adapted to receive current from said storage battery, a starter switch for controlling the operation of said starting motor, an electromagnet having a winding for operating said starter switch, a magnetic 20 switch in circuit with the winding of said magnet and controlling the operation of said magnet, a control circuit for the magnetic switch for connecting the magnetic switch with the battery independently of both the generator and the starting motor including a normally open switch manually movable to closed position and movable by the engine to open position and a second switch normally closed and adapted to be opened by the cut out relay when the engine runs under 25 its own power.
10. In an engine starter control system, the combination comprising, a storage battery, an engine driven generator for charging the battery, a cut out relay for connecting the generator with the battery, a starting motor adapted to receive current from said storage battery, a starter switch for controlling the operation of said starting motor, an electromagnet having a winding for operating said starter switch, a magnetic switch in circuit with the winding of said magnet and controlling the operation of said magnet, a control circuit for the magnetic switch for con- 30
- necting the magnetic switch with the battery independently of both the generator and the starting motor including a switch operated by engine suction, a second switch operated by said cut out relay, and a manually operated switch.
11. In an engine starter control system, the combination comprising, a storage battery, an engine driven generator for charging the battery, a cut out relay for connecting the generator with the battery, a starting motor adapted to receive current from said storage battery, a starter switch for controlling the operation of said starting motor, an electromagnet having a winding for operating said starter switch, a magnetic switch in circuit with the winding of said magnet and controlling the operation of said magnet, a control circuit for the magnetic switch for connecting the magnetic switch with the battery independently of both the generator and the starting motor including a normally open switch manually movable to closed position and movable by the engine to open position and a second switch normally closed and adapted to be opened by the cut out relay when the engine runs under 35 its own power.
12. In an engine starter control system, the combination which comprises, a storage battery, an engine driven generator for charging the battery, a cut out relay associated therewith, an electric starting motor for starting the engine, and a control circuit for connecting the battery with said starting motor, said control circuit including a relay magnet having a winding, a switch operated by the cut-out relay, a connection extending from said winding to said last-named switch and from said switch directly to the battery whereby when said last-named switch is closed said winding is connected directly with the battery, and a second switch for controlling 40 the action of the relay magnet winding.

JOHN B. DYER.
WILLIAM E. BROWN.
